(57) **CLAIM**

The ornamental design for a shoe, as shown and described.

DESCRIPTION

FIG. 1 is a lateral side view of a shoe showing my new design;

FIG. 2 is a front view thereof;

FIG. 3 is a medial side view thereof;

FIG. 4 is a rear view thereof;

FIG. 5 is a front-top perspective view thereof;

FIG. 6 is a bottom view thereof;

FIG. 7 is a front-lateral perspective view thereof; and,

FIG. 8 is a top view thereof.

The broken lines in the figures are for the purposes of illustrating portions of the shoe that form no part of the claimed design.

1 Claim, 8 Drawing Sheets
